CROSS DRUM BOILER

Perry R. Cassidy, Short Hills, N. J., assignor to
The Babcock & Wilcox Company, Bayonne,
N. J., a corporation of New Jersey

Application April 2, 1928, Serial No. 266,517
Renewed June 4, 1932

9 Claims. (Cl. 122—255)

This invention relates to a cross drum boiler that has a plurality of steam and water drums, and will be understood from the description in connection with the accompanying drawings in which Fig. 1 is a vertical section through an illustrative embodiment of the invention, and Fig. 2 is a section along the line 2—2 of Fig. 1.

In the drawings reference character 5 indicates steam and water drums that are parallel to each other. A row of vertically disposed headers is located below each drum, the alternate headers 6 of each row being uptake headers and the other headers 7 being downtake headers. Nipples 8 connect the downtake headers in the respective rows to the water space of the corresponding drums 5 and nipples 9 connect the upper ends of the uptake headers to the drums, these nipples extending into the drum to a distance above the normal water level therein and being curved outwardly, as indicated at 10.

Rows of inclined tubes 11 constituting banks of tubes connect the lower portions of the downtake headers on one side to the upper portions of uptake headers on the other side, these rows of tubes alternating and crossing each other with a few of the lower tubes in each row spaced farther apart than the others to decrease trouble due to slagging of the tubes. The headers 6 and 7 are stepped where the tubes enter the same, and are straight along the remaining portions so that the upper ends of the downtake headers and the lower ends of the uptake headers have straight sides. Nipples 12 connect the lower ends of the headers 6 and 7 to mud drums 13 on the respective sides. The headers 14 and tubes 15 leading therefrom are portions of a circulatory system between the drums 5 and the walls of the furnace, not shown.

An economizer is located in the space between the drums 5. Feed water inlet pipe 18 enters the header 19 from which rows of tubes 20 provided with return bends 21 lead to an upper header 22, these tubes and headers constituting the economizer. Tubes 23 lead from the header 22 to the drums 5.

The drums 5 are provided with dry plates 25 in the steam space thereof and connections 26 lead from the space above the dry plates 25 to superheater inlet headers 27 on opposite sides of the boiler. U-tubes 28 extend from the headers 27 into the space between the banks of tubes 11 and the economizer and are connected to the superheater outlet headers 29, from which outlets 30 lead to a steam main. The superheater tubes 28 may be supported by means of piers 31 that rest upon the upper tubes of the banks 11.

The drums 5 may be provided with equalizing connections 32 between the steam spaces thereof, and equalizing connections 32' between the water spaces thereof. These connections 32 and 32'

are preferably located outside of the boiler setting as indicated in the drawings.

Hot products of combustion from the furnace 33 below the tubes 11 pass upwardly in a single pass across the inclined tubes 11, superheater tubes 28 and economizer tubes 20, and thence pass out through the outlet 34 to the stack. Water that enters the drums 5 from the economizer passes downwardly through the nipples 8 on each side into the downtake headers 7, thence through the inclined tubes 11 where steam is generated. The mixture of steam and water then passes into the uptake headers 6, thence through the nipples 9 into the steam space of the drum, from which the steam goes to the superheater and thence to the mains.

I claim:

1. In a boiler, parallel steam and water drums, a row of substantially straight and vertically extending alternating uptake and downtake headers arranged side by side and connected to each drum by nipples, and rows of inclined tubes connecting the headers connected to one drum to those connected to the other drum, the upper ends of the nipples connecting said uptake headers to said drums extending above the normal water level in said drums.

2. In a water tube steam boiler having but one rectilinear gas pass, an exhaust gas flue at one end of the gas pass, a boiler setting, a steam and water drum located along each of two opposite sides of the flue and at the top of the boiler setting, a bank of economizer tubes located between said drums and extending across the gas pass, a bank of steam superheater tubes extending across the gas pass and located below the economizer tubes, a boiler furnace having walls located at one end of the setting, opposite gas pass wall portions formed by a plurality of parallel and aligned upright headers located above the furnace and below the respective drums, separate direct connections between each header and the drum directly above it, and boiler tubes directly connecting corresponding headers of said opposite wall portions so that alternate headers in each wall portion conduct fluid in a direction reverse to the direction of the fluid flow in the adjacent headers, the direct connections from the uptake headers terminating above the normal water level of the drum.

3. In a water tube steam boiler having but one rectilinear gas pass, a boiler setting, a furnace gas chamber having walls at one end of the setting, an exhaust gas flue at the opposite end of the setting, parallel and aligned uptake and downtake headers located so as to constitute substantially an extension of a wall of said chamber, a second set of similarly arranged headers constituting substantially an extension of the opposite wall of said chamber, two steam and water drums

located on opposite sides of the flue and arranged respectively above said sets of headers, cross circulators connecting the drums below their water levels, a direct connection between each header and the drum above it, boiler tubes directly connecting corresponding headers of the opposite sets, banks of superheater tubes located in the gas pass above said boiler tubes, and banks of economizer tubes located in the flue and between 5 and the drum above it, boiler tubes directly connecting corresponding headers of the opposite sets, banks of superheater tubes located in the gas pass above said boiler tubes, and banks of economizer tubes located in the flue and between 10 said steam and water drums, the direct connection from each uptake header terminating above the normal water level of its drum.

4. In a water tube steam boiler, a steam and water drum, a boiler furnace, a plurality of closely adjacent upright headers located side by side and positioned beneath the said drum so as to form a wall of a gas pass, direct connections between the tubes of alternate headers and the drum to conduct water to the headers from the 15 drum, uptake connections terminating above the normal water level in the drum and directly connecting the remaining headers to the drum to discharge steam and water into the drum, boiler tubes communicating with the headers and exposed externally to gases from the furnace to provide for the fluid movement above indicated, and a bank of superheater tubes extending transversely of the boiler tubes and located at the 20 level of said connections, said superheater tubes being arranged as loops extending into the gas 25 pass from opposite sides of the boiler.

5. In a water tube steam boiler, a steam and water chamber, walls forming a gas pass, a plurality of alternately arranged uptake and downtake headers located side by side so as to form substantially a continuation of said passageway, direct downtake connections between the downtake headers and the steam and water chamber to discharge water into the headers, uptake 30 connections terminating above the normal water level in said chamber and directly connecting the remaining headers to the chamber, upwardly and downwardly inclined boiler tubes communicating with the headers and exposed externally to the 35 furnace gases to provide for the fluid movements above indicated, and a superheater consisting of tube loops extending into the gas pass from the opposite sides adjacent the side along which the headers are arranged, said superheater tubes extending into the gas pass at the level of the 40 uptake and downtake connections.

6. In a water tube steam boiler installation having but one rectilinear gas pass, an exhaust gas flue at one end of the gas pass, a boiler setting, a steam and water drum located along each of two opposite sides of the flue and at the top of the boiler setting, a bank of economizer tubes located between said drums and extending across the gas pass at the level of the drums, a bank of 45 steam superheater tubes extending across the gas pass and located below the economizer tubes, a boiler furnace having a wall located at each end of the setting, opposite gas pass wall portions formed by a plurality of parallel and aligned uptake and downtake headers located in rows above the furnace and below the respective drums, separate direct uptake and downtake connections between each header and the drum directly above it, and boiler tubes directly connecting corresponding headers on said opposite wall portions 50 so that alternate headers in each wall portion

conduct fluid in a direction reverse to the direction of the fluid flow in the adjacent headers, said uptake connections terminating above the normal water levels of the drums.

7. In a water tube steam boiler installation 80 having but one rectilinear gas pass, a boiler setting, a furnace gas chamber having walls at the lower part of the setting, an exhaust gas flue at the upper part of the setting, parallel and aligned uptake and downtake headers located so as to constitute substantially an extension of a wall of said furnace gas chamber, a second set of similarly arranged uptake and downtake headers constituting substantially an extension of the opposite wall of said furnace gas chamber, a steam and water drum located on opposite sides of the flue and arranged respectively above each of said sets of headers, a direct uptake connection between each uptake header and the drum above it terminating above the normal water level of the drum, downtake connections directly connecting each of the remaining headers with the drum above it, boiler tubes directly connecting corresponding headers of said opposite sets so that a downtake header of one set is directly connected to an uptake header of the opposite set, banks of superheater tubes located in the gas pass above said boiler tubes and at the level of said connections, and banks of economizer tubes located in the flue 95 and at the levels of said steam and water drums.

8. In a water tube steam boiler, a boiler setting, affording but one gas pass, a first steam and water drum along the top of one wall of the setting, a second steam and water drum along 100 the top of the opposite wall of the setting, alternately arranged uptake and downtake headers forming an upright gas pass wall below each drum, horizontally inclined steam generating tubes extending from each downtake header to a 105 corresponding uptake header in the opposite gas pass wall, downtake nipples directly connecting each downtake header with the drum above it and terminating below the normal water level of the drum, uptake nipples directly connecting 110 each uptake header with the drum above it and terminating above the normal water level of the drum, a water tube wall header near each row of headers, connections leading directly from each wall header to the drum above it, cross 115 circulators connecting the drums beneath their water levels, a superheater consisting of tube loops extending into the gas pass from the sides of the setting adjacent one of the header walls and located on the level of the nipples, superheater supports located at an elevation below the tops of the headers and above the horizontally inclined tubes and an economizer extended in a flue between the drums with its bottom below 120 the tops of the drums.

9. In a boiler, parallel steam and water drums, a row of substantially straight and vertically extending alternating uptake and downtake headers arranged side by side connected to each drum by nipples and rows of inclined tubes connecting the 125 headers connected to one drum to those connected to the other drum, the upper ends of the nipples connecting said uptake headers to said drums extending to a level higher than the upper ends of the downtake nipples.

PERRY R. CASSIDY.
